CLAIM

We claim the ornamental design for a magazine well funnel, as shown and described.

DESCRIPTION

FIG. 1 is a perspective view from below of a magazine well funnel according to our new design.

FIG. 2 is a perspective view from above of a magazine well funnel according to our new design.

FIG. 3 is a top view of a magazine well funnel according to our new design.

FIG. 4 is a front view of a magazine well funnel according to our new design.

FIG. 5 is a right side view of a magazine well funnel according to our new design, the left side view being a mirror image thereof.

FIG. 6 is a back view of a magazine well funnel according to our new design.

FIG. 7 is a bottom view of a magazine well funnel according to our new design; and,

FIG. 8 is a side view of a magazine well funnel according to our new design inserted into a pistol.

The broken lines shown in each of FIGS. 1-8 depict one or more of a stabilization tab, a pin hole, and pistol body, all of which form no part of the claimed design in FIGS. 1-8.
